ERNEST H. SCHMIDT, OF CLEVELAND HEIGHTS, OHIO, ASSIGNOR TO NATIONAL MALLEABLE AND STEEL CASTINGS COMPANY, OF CLEVELAND, OHIO, A CORPORATION OF OHIO

DRAFT ATTACHMENT FOR RAILWAY VEHICLES

Application filed March 5, 1927. Serial No. 173,024.

My invention relates to improvements in draft attachments of the character shown in the application of Ernest H. Schmidt and Hubert L. Spence, filed January 19, 1927, 5 Serial No. 161,992, which matured into Patent No. 1,859,535, May 24, 1932, in which a draft equalizer and a buffing equalizer are used, and provides means for retaining the draft equalizer member in the coupler shank 10 even when the draft key has been removed so as to prevent the draft equalizer from being lost or mislaid, and also means for supporting the buffing equalizer upon the rear end of the coupler shank to maintain it in 15 such supported position for convenience of assembly as well as of operation. My invention also comprises various features which I shall hereinafter describe and claim.

Fig. 1 is a horizontal section of the rear end 20 of a coupler shank to which my improvements have been applied; Fig. 2 is a vertical section thereof; and Fig. 3 is a section on line III—III of Fig. 2.

Referring to the drawing, I have shown my 25 invention applicable to a car coupler having a shank of the construction shown in the application of Ernest H. Schmidt and Hubert L. Spence, Serial No. 161,992, filed January 19, 1927, for draft attachments. The shank A of 30 the car coupler has a horizontal slot 2 extending transversely therethrough, in which is seated a draft equalizer member 3, the rear face 4 of which is convex in two directions to correspond with the surface 5 which forms 35 the rear face of the slot 2 in the car coupler. The forward face 6 of the equalizer is concave in a vertical direction, so as to afford a bearing on the rear side of the draft key B through which draft stresses are transmitted 40 to the horizontal links or yoke arms C. To prevent the equalizer 3 from being accidentally removed or falling out and being lost, I preferably employ a keeper or retainer 7. This may be of C-shape, which may be applied 45 between the seats 8 and 9 for the draft key and the equalizer 3 by dropping it over the longitudinally extending reinforcing web 10 and bending its ends into the aperture 11 which extends through the web. When the keeper 7 is in position its upper face will not

extend beyond the face of the key seating surface 8, but will project above the surface 9 of the web 10 upon which the equalizer seats, and is situated so that there is not room to remove the equalizer when the keeper is in position, even though the draft key has been removed from the slot 2 and the coupler shank from the car A.

The rear end of the coupler shank has an arc-shaped rear surface 12, preferably struck 60 about the same vertical center as the surface 5, which bears against an equalizing buffing block 13, the forward face of which is curved in approximately the same arc as the surface 12 at the rear end of the shank. The buffing 65 block 13 is intended to bear upon its rear face 14 against the forward face of the front element or follower D of a draft gear, which is usually at right angles to the line of draft.

For the purpose of supporting the equalizing block 13 upon the coupler shank, I preferably form recesses 15 and 16 in the top and bottom of the coupler shank for reception, respectively, of a hook-shaped lug 17 which extends forwardly and downwardly at the 75 top of the buffing block, and a lug 18 which extends forwardly from the bottom of the buffing block. When the buffing block has been applied to the rear end of the coupler shank with the upper lug 17 seating in the 80 recess 15 of the shank and the lower lug 18 in the recess 16 at the bottom of the shank, the end of the lower lug may be upset by 85 striking it sharply upward. By reason of the rearwardly inclined upper surface 19 of the recess, the bottom lug 18, after it is bent, will prevent removal of the buffing block, while permitting radial movement of the block relative to the shank.

Both of the recesses 15 and 16 are arc-shaped so as to permit the buffing block to rotate about the center upon which the arc of the rear surface 12 of the shank is struck, so as to permit it to perform its equalizing function with reference to the rear end of the 90 coupler even though it is supported thereby.

It will be seen that the provision here made for retaining the draft and buffing equalizing members in operating position with reference to the shank, regardless of whether or 100

not the coupler has been applied to the car, renders easier the application of the coupler attachments described in the Schmidt and Spence application referred to above, and at 5 the same time prevents loss or removal of these parts.

As was pointed out in the Schmidt-Spence application above referred to, it is desirable to have the shank with the radial attachments interchange with the standard A. R. A. shank. It will be apparent from the drawing that the means herein shown for attaching the buffing block permits a construction in which the height of the buffing block does 10 not exceed the height of the adjacent portions of the shank and this coupler may be inserted as far as overall height is concerned in any attachments that receive a standard coupler. Also, as noted in said Schmidt-Spence application, the distance from the 15 rear of the key to the rear of the buffing block should be the same as the distance from the rear face of the draft key to the rear end of the standard coupler, thus permitting substitution of one shank for the other. The improved shank, moreover, is made as strong 20 as the standard shank by maintaining the cross-sectional area of the shank in the zone of the key slot, which is the weakest point, 25 at least as great as in the standard coupler.

The terms and expressions which I have employed are used as terms of description and not of limitation, and I have no intention, in the use of such terms and expressions, 30 of excluding any mechanical equivalents of the features shown and described, or portions thereof, but recognize that various structural modifications are possible within the scope of the invention claimed.

40. What I claim is:

1. In a coupler attachment, a coupler shank and yoke having horizontal aligned slots therein; a connecting key in said slots; an equalizer in the slot in the shank between the 45 key and the rear end of the shank providing a rotative bearing for the key in the shank; and a keeper for the equalizer located adjacent the center line of the coupler to limit the movement of said equalizer away from its 50 rotative bearing without interfering with the rotative movement of the equalizer in the slot during normal operating movements, said keeper being arranged to prevent accidental displacement of said equalizer from operative relation to said shank.

2. In a coupler attachment, a coupler shank, an equalizer arranged to transmit buffing stresses from said shank throughout the buffing movement thereof, and means for securing the equalizer to the shank, said means comprising a bendable lug on one of said members within the confines of the shank.

3. A coupler shank having a transverse key-slot extending therethrough, a draft 65 equalizer forming the rear portion of said

slot, a yoke connected to said shank, said draft equalizer being of a width substantially equal to the width of the coupler shank and means within the shank for securing said equalizer to the shank even when the latter is 70 disconnected from the yoke, the equalizer having substantially flat uninterrupted upper and lower surfaces permitting the ready insertion and removal thereof, said shank having a solid portion to the rear of said slot 75 against which portion said equalizer is adapted to bear.

4. In a coupler attachment, a yoke, a coupler shank connected to said yoke and having interior and exterior arc-shaped surfaces; a 80 pair of equalizing members engaging said surfaces and supported by and movable with said shank in both buff and draft, and means cooperating with said members and said shank for limiting the longitudinal movement of said members relative to said shank even when the latter is disconnected from said yoke and providing for lateral movement between said members and said shank, 85 one of said members being active in draft and the other in buff.

5. In a coupler attachment, a coupler shank, a yoke connected thereto, said shank having separate draft and buffing equalizer members movable therewith and radially 90 thereto and means securing said members to said shank even when the latter is disconnected from said yoke, said means being entirely within the confines of said shank and preventing accidental removal of said members.

6. In a coupler attachment, a coupler shank, a yoke, a pair of equalizing members supported by said shank, one of which is active in draft and the other in buff, and means 100 on said shank and members whereby said shank and members are connected together even when said shank is disconnected from said yoke, one of said means being on the interior of the shank and the other of said 105 means on the exterior of the shank.

7. In a coupler attachment, a coupler shank adapted for connection to a yoke, a pair of equalizing members supported by and movable with the shank, draft stresses being 110 transmitted through one of said members and the buffing stresses through the other, and retaining means limiting the movement of each of said members longitudinally relative to the shank and securing said members to the 115 shank even when the latter is disconnected from said yoke.

8. A coupler shank having a transverse key slot extending therethrough, portions of said shank completely surrounding said slot, 120 a draft equalizer forming the rear portion of said slot, a yoke connected to said shank, said draft equalizer being of a width substantially equal to the width of the coupler shank, and means secured to the shank for 125 130

holding the equalizer to the shank even when the latter is disconnected from the yoke, the equalizer having substantially flat uninterrupted upper and lower surfaces permitting the ready insertion and removal thereof.

- 5 9. In a coupler attachment, a coupler shank, a yoke, a pair of equalizing members supported by said shank, one of which is active in draft and the other in buff, and means on said shank and members whereby
10 said shank and members are connected together even when said shank is disconnected from said yoke, one of said means being on the interior of the shank and the other of
15 said means on the exterior of the shank, both of said means lying entirely within the confines of the shank.
